F. D. RICH

INSIDE TUBE CUTTER

Filed Feb. 17, 1925

Inventor

Frederick D. Rich

By his Attorney

John E. Hubbard

UNITED STATES PATENT OFFICE.

FREDERICK D. RICH, OF EDGEWATER, NEW JERSEY; ADELAIDE RICH EXECUTRIX OF
SAID FREDERICK D. RICH, DECEASED.

INSIDE TUBE CUTTER.

Application filed February 17, 1925. Serial No. 9,725.

The object of my present invention is to provide a simple, efficient, durable and easily operable tool for insertion within a pipe or tube to sever the pipe or tube from the inside.

The various features of novelty which characterize my invention are pointed out with particularity in the claims annexed to and forming a part of this specification; but for a better understanding of the invention, its advantages and specific objects attained with its use, reference should be had to the accompanying drawings and descriptive matter in which I have illustrated and described preferred embodiments of my invention.

Of the drawings:

Fig. 1 is an elevation in which the tube is operated on and portions of the tool are in section;

Fig. 2 is a section on the line 2—2 of Fig. 1;

Fig. 3 is a section on the line 3—3 of Fig. 1;

Fig. 4 is a section taken similarly to Fig. 2, and showing a modification in which three cutting wheels are substituted for the single cutting wheel of Figs. 1—3; and

Fig. 5 is a cross section on the line 5—5 of Fig. 4.

In the drawings, and referring first to the construction shown in Figs. 1, 2, and 3, a tool body is shown formed of inner and outer parts or end to end sections A and A'. The end of the inner section A adjacent the section A' is formed with a cylindrical socket or chamber A² which is internally threaded to its outer end to receive the threaded inner end of the outer section A'. By this threaded connection the sections A and A' are rigidly secured together in the operative condition of the tool, but may be separated when occasion requires. The section A is formed with a transversely extending slot A³ at the inner end of the chamber A² having its outer side in open communication with the latter. Mounted in the slot or guideway A³ is a tool support D, which may advantageously be a block of steel. The block D is bifurcated at its outer end to receive the cutter E, which is in the form of a steel disk journaled on a shaft E', the ends of which are held in the forks D' of the block D. The guideway A³ is enlarged at its outer end A⁴ to provide clearance for

the cutter disk, the diameter of which is ordinarily greater than the width of the block D.

The block D is moved radially of the tool body by means of a rotating cam C of cylindrical outline which fits and is rotatable in the chamber A³, with its inner end bearing against the adjacent side of the block D and its outer end bearing against the inner end of the body section A'. A spiral cam groove C' is formed in the end of the cam C adjacent the block D. The cam groove C' receives a cam lug or projection, carried by the member D, and advantageously in the form of a hardened steel pin D² having one end secured in a socket formed for the purpose in the member D. The cam C is rotated in its chamber to thereby give radial movement to the member D by means of a shaft B which passes axially through the section A', made hollow for this purpose, and has its tapered inner end entering a tapered socket C³ formed in the member C, and in which it is secured by means of a tapered key C⁴.

At its outer end the section A' and the shaft B have a ratchet connection. This connection is formed by axially extending ratchet teeth A⁵ on the member A at its outer end and normally in mesh with the ratchet teeth A⁶ formed on the adjacent end of a member A⁷. The latter surrounds the shaft B and is movable axially of the latter to engage and disengage the ratchet teeth A⁵ and A⁶ but is prevented from angular movement with respect thereto by means of a suitable key or spline, shown as formed by a radially extending stud-bolt B⁴ threaded into the shaft B and having its head received in an axially elongated slot A⁸ in the member A⁷. The ratchet teeth of the member A⁷ are normally held in mesh with the ratchet teeth A⁵ on the end of the body section A' by means of a helical spring B' received in a recess or enlargement of the bore of the member A⁷ with the inner end of the spring bearing against the inner end of the wall of the recess and with the outer end of the spring bearing against a collar-like enlargement B² of the shaft B which is slidably received in the outer end of the recess in the member A⁷.

At its outer end the shaft B is formed with a transverse opening or openings B³ to receive a handle or cross bar by which

the shaft B may be rotated. To facilitate assembly and disassembly of the apparatus, the section A' is advantageously flattened at its sides, as indicated at A⁶, for engagement by a wrench, and the section A is formed at its inner end with a polygonal extension A¹⁰ adapted for wrench engagement. A set screw D² axially mounted in the inner end of the section A' and having its inner end extending into the guideway A³ and received in a recess or slot D⁴ formed in the tool support D, normally limits the radial movement in either direction of the tool support D, and in particular prevents the accidental movement of the tool support D out of its guideway A³ through the end A⁴ thereof. A split collar F surrounding the tool section A' and adjustable axially of the latter, may be secured in any desired position along the length of the latter by a clamping screw F'. The collar F forms a stop abutting against the end of the tube G to be severed and fixing the distance from the tube G end of the cut made by the cutter when the tool is inserted as shown in Fig. 1 into a tube G to be severed. The parts are so proportioned that the inner end of the tool may be freely entered into the tube to be severed when the cutter E is radially retracted.

With the tool entered as shown in Fig. 1, into a tube G which is to have its adjacent end cut off, the severing operation proceeds as follows: The shaft B is first rotated relatively to the section A' in the direction (counter clockwise) permitted by the shape of the ratchet teeth A⁵ A⁶ to advance the cutter D until it bites into the inner wall of the tube G. The shaft B, and thereby the tool as a whole, is then given a turn in the opposite (clockwise) direction, thereby cutting a circular groove or kerf in the tube. The shaft B is then again rotated in a counter clockwise direction relative to the tool body the distance of one or more ratchet teeth A⁶ to cause the disk E to bite deeper into the tube, and the tool is then again rotated in the clockwise direction for one complete turn, and these operations are continued until the tube is severed. After the severing operation is completed, the cutter E may be retracted by moving the member A⁷ away from the section A' to separate the ratchet teeth on the members, and then rotating the shaft B and member A⁷ relative to the tool body in the clockwise direction until the cutter is sufficiently retracted.

The tool shown in Figs. 1, 2, and 3 is simple in construction, and reliable and effective in operation. The radial advance of the cutter holder by means including the spiral cam groove C' permits of a relatively easy cutter advance motion, since the cam groove may well be shaped as shown in Fig. 3 so that the radial cutter movement will be

proportional, and desirably small with respect to the angular movement of the cam C in its chamber A² throughout the entire range of cutter movement. The elongation of the active cam surface by which the radial movement of the cutter holder is effected which the construction permits, increases the leverage, and decreases the force required to force the cutter into the work, and also makes it possible to divide up the advancing movement of the cutter block into a relatively large number of small and definite steps, one for each of the ratchet teeth, the extent of each such step depending, of course, upon the pitch of the ratchet teeth. Of course the radial advancement of the cutter at each adjustment may result from a relative angular movement of the members A' and A⁷ corresponding to one, two, three or more of the ratchet teeth, depending on the character of the work and the conditions of operation. The construction is one permitting the ready and relatively inexpensive machining of the parts employed, and the tool can readily be taken apart, and the parts liable to wear, notably the cutter E, its supporting shaft E', the cam pin D², may readily be replaced when this is necessary. Furthermore, the cam member C itself can be readily replaced when wear makes this desirable, or changes in the operating conditions makes it desirable to replace one cam C by another having a spiral cam of different pitch or shape.

In Figs. 4 and 5 of the drawing, a modified construction is shown in which a plurality of cutters is substituted for the single cutter of Fig. 1. In this construction three cutter wheels E¹⁰ mounted on blocks D¹⁰ are moved simultaneously in radial directions, each within a corresponding radial recess A¹³ in the body section A¹¹, which corresponds with the body section A of Fig. 1. The simultaneous movement of the three cutter wheels is obtained by so positioning the pins D¹² in the respective blocks D¹⁰ that these pins D¹² all engage at different points within the same single spiral groove C¹¹. All three cutter wheels E¹⁰ may thus be simultaneously forced into engagement with the pipe and thereafter simultaneously rotated and radially advanced to cut the pipe.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what

I claim as new and desire to secure by Letters Patent, is:

1. An inside pipe cutting tool comprising a tool body adapted to be inserted in a pipe to be severed and formed with inner and outer separable sections, said inner section being an integral body formed with a chamber open at the outer end of the section and with a transverse guideway open at its outer side to the inner end of said chamber, a cutting tool support mounted in said guideway with a cam engaging projection extending into said chamber, a tool advancing cam rotatably mounted in said chamber and formed with a spiral groove in its inner end receiving said tool support projection, a shaft member rotatably mounted in the outer section of said tool body and detachably secured to said cam, a ratchet connection between said shaft and said outer body section permitting rotation of said shaft relative to said outer body section in one direction while normally preventing such relative rotation in the opposite direction.
2. An inside pipe cutting tool comprising a tool body adapted to be inserted in a pipe to be severed and formed with inner and outer separable sections, said inner section being formed with a chamber open at the outer end of the section and with a transverse guideway open at its outer side to the inner end of said chamber, a cutting tool support mounted in said guideway with a cam engaging projection extending into said chamber, a tool advancing cam rotatably mounted in said chamber and formed with a spiral groove in its inner end receiving said tool support projection, a shaft member rotatably mounted in the outer section of said tool body and detachably secured to said cam, a ratchet connection between said shaft and said outer body section permitting rotation of said shaft relative to said outer body section in one direction while normally preventing such relative rotation in the opposite direction.

cured to said cam, a ratchet connection between said shaft and said outer body section permitting rotation of said shaft relative to said outer body section in one direction while normally preventing such relative rotation in the opposite direction, said tool support being formed with a recess in its inner side, and a bolt axially threaded through the inner end of said inner section and entering said recess.

3. An inside pipe cutting tool comprising a body adapted to be inserted in a pipe to be severed and consisting of inner and outer sections, said inner section being formed with an axial chamber in its outer end, the outer portion of which is internally threaded, and the outer section having its inner end externally threaded and screwed into said chamber to detachably connect said sections, said inner section being formed with a transverse guideway open at its outer side to the inner end of said chamber, a tool support mounted in said guideway and formed with a projection entering said chamber, a tool advancing cam rotatably mounted in said chamber and formed with a spiral groove in its inner end, a shaft receiving said projection rotatably mounted in the outer section of said tool body, a tapered key passing transversely through said shaft and said cam to detachably secure them together, a ratchet connection between said shaft and said outer body section permitting rotation of said shaft relative to said outer body section in one direction while normally preventing relative rotation in the opposite direction.

Signed at New York in the county of New York and State of New York this 16th day of February, A. D. 1925.

FREDERICK D. RICH.
